UNITED STATES PATENT OFFICE

HOMER T. DARLINGTON, OF WEST CHESTER, PENNSYLVANIA, ASSIGNOR, BY MESNE ASSIGNMENTS, TO OIL CORPORATION OF AMERICA, A CORPORATION OF DELAWARE

PROCESS OF TREATING HYDROCARBONS

Original application filed April 22, 1927, Serial No. 186,005. Divided and this application filed August 11, 1928. Serial No. 298,887.

I have invented a new and useful process of the treatment of fluid hydrocarbons of which the following is a description:

In the distillation and cracking of petroleum hydrocarbons where the production of low-boiling hydrocarbons from higher-boiling hydrocarbons is an object, I have found that the attainment of that object is considerably aided by the treatment of the hydrocarbons in the manner hereinafter set forth, and that this treatment is very effectively given in a reaction chamber of special construction devised by me, and hereinafter described. This treatment takes place preferably, though not necessarily, at a point intermediate the stage of partial cracking in a still or kindred apparatus and the stage of dephlegmation or separation.

My process will be better understood if, in connection with the description of it, reference is made to the accompanying drawing, and the following description of the reaction chamber I have invented.

In the drawing:

Figure 1 is a vertical section of the reaction chamber; and

Fig. 2 is a plan of the same;

Fig. 3 is a diagrammatic showing of the circulatory system including means for heating the first cyclic stream.

Like figures indicate similar parts.

This is a division of my pending application Serial No. 186,005, filed April 22, 1927, for process and apparatus for treating hydrocarbons.

The reaction chamber is made up of a plurality of tubular members arranged parallel to each other longitudinally and connected by tubes, of which I have shown one arrangement only. This construction is adapted, among other things, to promote circulation. The number and length of these tubular members may vary and they may, and, under some conditions, should, be of different lengths.

In the drawing, 3 is the portal through which hydrocarbon, which has been distilled and partly cracked, enters the reaction chamber under conditions of temperature and superatmospheric pressure conducive to cracking, from the still A at 1, and is directed

by the deflector plate 2 in the course indicated by the arrows circulating around through 3, 4, 5 and 6, and then through 7, 8, 9, 5 and 7 and passing to 14, which I call a zone of non-circulatory turbulence, located in the terminal tubular member 8 beyond and above the line of circulation therethrough wherein the hydrocarbon does not circulate to any substantial degree but owing to the motion communicated by the circulation in other parts of the chamber and the continuous or intermittent feeding of hydrocarbon thereto and discharge of hydrocarbon therefrom is in a state of turbulence.

This zone of non-circulatory turbulence may be so positioned in relation to the zone of active circulation that the movement therein has a churning effect. In some instances this is desirable and produces better results. This zone of non-circulatory turbulence is preferably, as shown, an integral part of one of the tubular sections of the reservoir chamber.

12 is a means of discharging vaporized hydrocarbons from the zone of non-circulatory turbulence and feeding them to a dephlegmator, separator or other apparatus for further treatment. 10 shows an optional oil level in the zone of non-circulatory turbulence, which level may vary as required by the character of hydrocarbon and working conditions employed, and 11 is an indicator or other means of ascertaining the oil level.

Valve controlled means 13 are provided for the introduction, as and when desired, of a catalyst, a gas, steam, or a treating or other agent. Such treating agent may suitably be of the type referred to in my Patent No. 1,614,660. The addition of a catalyst, gas, steam, a treating or other agent, or two or more of them, may be made at the point indicated or at any other part of the reaction chamber, or to the zone of non-circulating turbulence alone. 15 shows valve controlled alternative means for introducing new stock, or stock that has been treated.

Heavy fractions, such, for example, as may be employed in the making of lubricating oil, deposited carbon, and any hydrocarbon it is not desired to treat further at the time may

be withdrawn through the valve controlled outlet 16. Efficiency in the operation of my said process and the use of my said apparatus is promoted by controlling the temperature 5 in the zone of non-circulatory turbulence, and provision is therefore made for the controlled regulation of temperature therein by the admission therein at will of fresh oil or other stock through a valve controlled line 10 17. Any other approved method of controlling and regulating the temperature in this zone may be used instead of the one shown and described.

I have sought to combine and arrange the 15 several parts of this reaction chamber in the most convenient and practical manner for effective use, but I do not confine myself to the embodiment of my invention shown, and I may vary the form and character of the several parts and the method of assembling them 20 and still have an apparatus embodying the principles which make my apparatus new and distinct.

This reaction chamber may, and ordinarily 25 should, be insulated and it may have means of heating (not shown) either direct or by heat interchange in any approved manner. While I prefer that hydrocarbon should be raised to a cracking temperature in a still 30 before its introduction to the reaction chamber, it may be preheated in any manner desired and the reaction chamber used as a combined still and reaction chamber. While 35 mechanical means of circulation within the reaction chamber, other than that provided by the addition of a catalyst, gas, steam or a treating agent when used, is ordinarily not required, the reaction chamber may have in it mechanical means of circulation, such as 40 paddles, a propeller 18 or an impeller operated by an external source of power, and it should be provided with such a means of circulation when not connected, as it is in the drawing, to a still or other preliminary treating 45 apparatus having such mechanical means of circulation.

I have found in actual practice that a multiplicity of tubular members arranged as shown in the drawing promotes circulation, 50 and when these parallel tubular members exceed two, the circulation of the hydrocarbons increases progressively from the place of entry and in the tubes more distant therefrom is exceedingly active, and that this 55 rapid circulation aids the cracking of hydrocarbon within the reaction chamber and causes the yield of greater quantities of more desirable products.

In the practical use of this reaction chamber and the practice of my process, I feed 60 an oil stock, preferably continuously, but intermittently if desired, to a still or any approved type, having suitable means of heating and applying pressure, and preferably, 65 though not necessarily, mechanical means of

promoting circulation. I maintain in the still a temperature and pressure conducive to cracking and pass the oil at cracking temperature and pressure in liquid form through the portal 3 into the reaction chamber. I then circulate the oil in the apparatus as shown to the zone of non-circulatory turbulence already described. There it vaporizes and the vapors pass through a pipe line controlled by the valve 12, or other connection, preferably 70 to a diphlegmator, but they may pass to a separate or other apparatus for further treatment.

To aid in the cracking and the vaporizing, 75 I introduce through means provided for that purpose, at 13, or elsewhere if preferred, a catalyst, gas, steam or treating agent, or two or more of them, or I may, if I prefer, omit this addition.

I have found that circulation of the peculiar kind shown, the agitation of the hydrocarbons in a zone of non-circulatory turbulence and the presence of a treating agent in the hydrocarbon while circulating and also 80 while in the zone of non-circulatory turbulence, each effectually contribute to the cracking and vaporization of the hydrocarbons and each help to produce more and higher grade products than can be otherwise obtained, and that each one of them alone has 85 some effect, but that they work more efficiently when some or all are used in combination.

The invention will more readily be understood from the following example. Cracking stock, suitably gas oil, is heated in the still 1 to a temperature about 850° F., and is supplied at this temperature into portal 3. The temperature in the tubular members 5 and 8 will be somewhat lower, for example, around 825° F. The pressure may be maintained by the valve 12 at about two hundred pounds. It will be understood that this pressure may be varied so as to maintain the bulk of the oil in the system liquefied. The upper end of the tubular member 8 is maintained at about 600° F., this temperature being controlled by the admission of fresh gas oil through the line 17. This temperature may be adjusted so as to control the nature of the vaporized product. Thus when the temperature of the vapor space above the surface 10 is maintained about 280° F., substantially commercial gasoline is distilled over. As a treating agent, bentonite may be employed. Said bentonite may be brought into suspension in a mixture of water and gas oil and may be introduced by the line 13. Suitable proportions are, 10 parts, by weight, of bentonite, 45 parts of water, and 45 parts of oil. The suspension may be introduced at the rate of about three or five gallons per one hundred gallons of oil treated, although greater or less quantities of the suspension may be employed.

1. The process of cracking hydrocarbon oil comprising cyclically circulating oil in three cyclic streams of oil undergoing liquid phase cracking, each of which is contiguous with 5 one of the others, heating the first of said streams, the second of said streams being contiguous with the first for a portion of its length and receiving heat therefrom by conduction and likewise transmitting heat from 10 the second to the third stream by conduction.
2. The process of cracking hydrocarbon oil comprising cyclically circulating oil in three cyclic streams of oil undergoing liquid phase cracking, each of which is contiguous 15 with one of the others, heating the first of said streams, the second of said streams being contiguous with the first for a portion of its length and receiving heat therefrom by conduction and likewise transmitting heat 20 from the second to the third stream by conduction, the third stream being in contact with oil which is substantially non-circulatory.
3. The process of cracking hydrocarbon 25 oil comprising cyclically circulating oil in three cyclic streams of oil undergoing liquid phase cracking, each of which is contiguous with one of the others, heating the first of said streams, the second of said streams being 30 contiguous with the first for a portion of its length and receiving heat therefrom by conduction and likewise transmitting heat from the second to the third stream by conduction, the third stream being in contact 35 with oil which is substantially non-circulatory, and withdrawing vapors from the non-circulatory zone.

In testimony whereof, I have hereunto set
my hand this 9th day of August, 1928.
